UNITED STATES PATENT OFFICE.

WILLIAM L. BEDINGER, OF SPRINGVILLE, ALABAMA.

FIRE-ESCAPE.

1,168,465.

Specification of Letters Patent. Patented Jan. 18, 1916.

Application filed February 26, 1915. Serial No. 10,754.

To all whom it may concern:

Be it known that I, WILLIAM L. BEDINGER, a citizen of the United States, and resident of Springville, county of St. Clair, 5 State of Alabama, have invented certain new and useful Improvements in Fire-Escapes, of which the following is a specification.

This invention relates to an apparatus for 10 saving life and is particularly adapted for use as a means of escape from a tall building in case of fire and as a means for escape from an aerial machine in case of accident.

It has been my purpose to make a device 15 operating on the principle of a parachute which will be simple in construction and which can be rolled or folded into a very compact form occupying very little space and weighing very little.

20 A further object has been to so make the construction that it will be automatic in its operation when it is used for the purpose of making an escape and it will then not be necessary for the person wishing to escape 25 to make any complicated adjustments. The device can be rolled into such compact form that it may be attached to the side of a suit case and then easily carried by a traveler and when it is desired to use the device it is 30 simply necessary to fasten a catch to some solid support and to fasten a belt around the waist of the user.

The novel features of the invention will 35 be apparent from the following description taken in connection with the drawings.

In the drawings—Figure 1 is a side view 40 of the apparatus embodying my invention partly distended under the weight of the user; Fig. 2 is a similar view with the bag-like support fully distended and released from the fixed support; Fig. 3 is a view of 45 the device in folded condition with the automatically releasable catch holding it to a fixed support; Fig. 4 is an enlarged detail view partly in section of the releasable catch; Fig. 5 is a detail sectional view of a 50 portion of the spiral spring in the free marginal edge of the bag at its open end; and Fig. 6 is a sectional view of a case showing my device therein in folded condition.

In the drawings I have not undertaken to 55 show the parts in proper proportion, but have merely shown them in their proper operative relation so as to make clear how the device is to be used. Those skilled in the art will of course make the proportions to suit

the requirements of the particular case and the size of the bag-like member may be varied for persons of different weights.

In the drawings I have shown a bag-like member 10 which may be made of any suitable light flexible and strong fabric or material which can be folded or rolled into a small space. The bag is closed at its upper end and at its lower end there is a spring 60 around the margin 11 tending to open the mouth of the bag. I preferably make this spring in the form of a spiral coil as shown in Fig. 5 so that it can be easily compressed and bent to shape in rolling or folding the 65 bag, but which will at once expand, opening the mouth of the bag, when the confining means is released. To the lower open end of the bag I secure a flexible means 13 which may be a rope or cord for supporting the 70 person from the bag, this cord being secured to a belt 14 which may pass around the body of the user below the arms with the point of attachment to the rope 13 at the user's back. The belt of course may be buckled in front 75 and when in place on the operator it does not interfere with the free movement of his arms or his body. The rope 13 is connected to the margin 11 of the bag by means of the flexible ropes or cords 15. 85

At the upper closed end of the bag and securely fastened thereto is a section 16 which in turn is connected by the cord 17 to the releasable catch 18. This releasable catch 18 has mounted on it a lever 19 hinged 90 at 20 and having an end 21 extending through an opening 22 in the side member 23 of the bifurcated end of the catch. The end 21 passes over to and preferably into the side member 24. The lower end of the 95 lever 19 is pressed outward by the coil spring 25 so as to normally maintain the end 21 in the position shown in Fig. 4, this spring 25 bearing on the lower projecting face 26 of the catch. A cord 27 is secured to the lower end of the lever 19 at 28 and passes through an opening in the part 26 and down through the bag-like member to the end of the rope 13 where it is fastened. The length 100 of this cord 27 is such that a pull on the rope 13 will tighten the cord 27 before the bag 10 is fully distended so that the spring 25 will be compressed and the end 21 of the catch will be pulled back to the position shown in Fig. 2. The end 21 normally 105 passes through the ring 29 which may be secured to a fixed support 30 and when the end 110

21 is pulled back to the position shown in Fig. 2 the catch is automatically released from the support 29 so that the bag-like parachute may descend with the passenger.

5 It will of course be understood that my invention is not limited to the specific form of the catch mechanism above described. The fixed support 29 may of course be secured into some fixed part of a building 10 near the window or into some part of the aeroplane or aerial machine, or the ring 29 may be connected to a cord or rope 31 as shown in Fig. 6 which may be secured to any suitable fixed support.

15 When the device is not in use it may be rolled up commencing at the bottom and compressing the coil spring 12 so as to make of the device a compact bundle, as shown in Fig. 3. In order to hold the device in shape

20 when so rolled up I make use of any suitable catch or mechanism. In the drawings I have shown such mechanism consisting of the ball and socket releasable catch such as will ordinarily be found on men's clothes.

25 The ball part 32 of the catch is shown fastened to the side of the bag part way down from the top and the socket member of the catch is in the part marked 16 at the top. When the bag is rolled into compact shape

30 the socket and ball are brought together and engage each other. In this means for releasably holding the bag in folded condition I make use of a loop 33 on or secured to the rope 13, this loop being placed over the ball 35 part of the releasably holding means before it engages the socket part so that a pull on the rope 13 will separate the ball from the socket and will permit the bag to unfold. As soon as this happens the spring 12 will

40 open the mouth of the bag so as to permit air to enter it and to distend it fully.

The folded bag-like life saving device may be placed in a casing 34 having a telescoping bottom 35 and in this instance the rope 45 31 may be made to pass out through one side of the casing so that it can be attached to a fixed support. If desired the rope 13 can also pass out through the opposite side of the casing with the belt 14 accessible to the 50 user of the device. Owing to the material and construction of the device it will be in very compact and light form when in the casing 34 and that casing can be easily strapped by a traveler to the side of his suit case and carried with him wherever he goes. It is in the form of a flat thin box and will 55 not be longer than the ordinary suit case.

In the operation of the device the person using it after seeing that the automatic 60 catch 18 is properly secured to a fixed support by means of the end 21 simply fastens the belt 14 around the waist with the rope 13 on the back. The operator then simply jumps from the window of a building or 65 from the aeroplane and the bag-like device

will be automatically opened and distended and released from the support so that it will support the operator like a parachute. The first operation is the release of the ball and socket holding means 32 which allows the 70 bag to unfold and the next thing which takes place is the release of the catch 18 so as to let the entire apparatus descend. When the casing 34 is used the operation may be exactly the same and in that case the 75 upper half of the casing may be left on the fixed support and the lower half may descend with the parachute. Owing to the simple construction the operator of an aeroplane may adjust a belt around his waist in times 80 of no danger and if by accident he is thrown or falls or jumps from the machine my life saving device will automatically act without any thought on his part.

What I claim is:—

1. A life saving apparatus comprising a 85 parachute of flexible fabric in bag-like shape adapted to be folded or rolled into a bundle of compact form, flexible means tending to open the mouth of said parachute, releasable 90 means for holding said parachute in said compact form, a flexible connection from said parachute for supporting a person, and means operated by said flexible connection for releasing said holding means. 95

2. A life saving apparatus comprising a 100 parachute of flexible fabric in bag-like shape adapted to be folded or rolled into a bundle of compact form, flexible means tending to open the mouth of said parachute, releasable 105 means for holding said parachute in said compact form, a flexible connection from said parachute for supporting a person, means operated by said flexible connection 110 for releasing said holding means, a catch secured to said parachute adapted to releasably engage a support, and means brought into operation as said parachute is distended for releasing said catch from the support. 115

3. A life saving apparatus comprising a 120 member provided with a releasable catch for engaging a support of a foldable parachute secured to said member, releasable means for holding said parachute in folded condition, a flexible connection from said parachute to 125 support a person, means operated by said flexible connection for releasing said holding means upon the first pull on said flexible connection, and means operated by the weight of the person for releasing said catch before said parachute is fully distended. 130

4. A life saving apparatus comprising a 135 parachute of flexible fabric in bag-like shape adapted to be folded or rolled into a bundle of compact form, a catch secured to said 140 parachute at its closed end adapted to releasably engage a support, a connection to the open end of the parachute to support a person, and means operated by the weight of the person for releasing said catch. 145

5. A life saving apparatus comprising a
parachute of flexible fabric in bag-like shape
adapted to be folded or rolled into a bundle
of compact form, flexible means tending to
open the mouth of said parachute, releasable
means for holding said parachute in said
compact form, a catch secured to said para-
chute at its closed end adapted to releasably
engage a support, a flexible connection to
the open end of the parachute to support a
person, and means operated by a pull on said
flexible connection for first releasing said
holding means and then releasing said catch.
6. A life saving apparatus comprising a
parachute of flexible fabric in bag-like shape
adapted to be folded or rolled into a bundle
of compact form, flexible means tending to
open the mouth of said parachute, releasable
means for holding said parachute in said
compact form, a flexible connection from 20
said parachute for supporting a person, a
thin flat substantially rectangular casing
surrounding said folded apparatus adapted
to be strapped to the side of a suit case said
casing being made up of telescoping parts 25
and said flexible connection passing through
one of said telescoping parts and adapted to
be secured to the body of a person.

In testimony whereof I affix my signature
in presence of two witnesses.

WILLIAM L. BEDINGER.
